Primary Examiner — Mehri F Bajoul(74) *Attorney, Agent, or Firm* — Minder Law Group;
Willy H. Wong(57) **CLAIM**

The ornamental design for a toy remote control, as shown and described.

DESCRIPTION

FIG. 1 is a front view of a toy remote control in accordance with the present invention.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines show portions of the toy remote control that form no part of the claimed design. The “ROBOT KIDDY” not forming part of the claimed design is an EU registered trademark of P&C International Development Limited.
